SOFA BED

Robert Allen Burton, High Point, N. C., assignor to
 Burton Upholstery Company, a corporation of
 North Carolina

Application December 31, 1942, Serial No. 470,772

7 Claims.

(Cl. 5—37)

The present invention relates to sofa beds, and particularly to a hinge construction for pivotally connecting the seat and back sections of the sofa bed to each other and to the bed frame.

At the present time, due to the shortage of metal, it has become necessary in many instances to change over from metal to wooden parts or elements in the furniture industry. For instance, where heretofore it has been customary to form the hinge elements which connect the seat and back sections to each other and to the frame or base substantially of metal, it is now necessary to entirely re-design this structure so that the several elements may be formed wholly or in part of wood or other non-metallic material.

One of the problems facing the manufacturer is to provide a non-metallic construction which will be sufficiently sturdy to sustain the weight of the seat and back sections, particularly when the device is being converted from sofa to bed position and vice versa. The present invention is designed to solve this problem and to provide a construction which will readily take the place of the metal structures and be sufficiently sturdy to effectively withstand the strains and stresses usually imposed upon the metal hinge elements.

With the foregoing and other objects in view, the invention will now be more fully described, reference being had to the accompanying drawings in which:

Figure 1 is an enlarged detail view, showing the hinge construction in full open or bed position;

Figure 2 is an enlarged detail view, showing the seat raised to permit the notch of the latch to engage the shoulder on the rail;

Figure 3 is a similar view, showing the back raised by the seat to a normal "couch use" position;

Figure 4 is a similar view, showing the seat lifted and moved far enough to the rear to cause the elevating dog to engage the shoulder on the rail;

Figure 5 is a similar view, showing the dog tripped in the downward movement of the seat;

Figure 6 is a fragmentary top view of the associated seat, back and bed frame members;

Figure 7 is a vertical section taken on line 7—7 of Figure 1;

Figure 8 is a vertical section taken on line 8—8 of Figure 1;

Figure 9 is a detail view of the latch element;

Figure 10 is an outside face view of the complete frame outline, on a reduced scale, in relation to the dotted outline of the sofa, and

Figure 11 is a view of a modified form of the invention.

Referring now to the drawings, and particularly to Figure 10, there is disclosed a sofa bed 10 incorporating the construction of the present invention. This bed comprises a base or frame 11 supporting the seat and back sections 12 and 13, respectively. As is usual in pieces of furniture of this type, the base or bed frame 11 is of substantially rectangular formation, comprising front and rear panels 14 and 15, respectively, and end panels 16. Legs or other suitable supporting elements 17 are attached to the base 11 and support the same in slightly elevated position. Upon the outer face of each end panel 16 is mounted a hinge supporting bracket 18. At the upper end of each bracket 18 is a fixed pivot 19, about which the seat and back sections 12 and 13 are mounted, to swing to different positions of adjustment, as will be hereinafter described.

Since each end section incorporating the hinge elements is identical in construction, only one will be described in detail, but it is to be understood that there is a set of these elements at each end of the base 11, pivotally secured to its support 18 by the fixed pivot 19. While substantially all of the elements of these sections are preferably formed of wooden parts, it is to be understood that the invention is not necessarily limited in this respect, and that these elements may be made of other suitable available material.

Referring now to Figures 1 to 6, there is disclosed the preferred form of the invention. The back section 13 is preferably of rectangular formation, including a longitudinally extending outer panel 20 and end panels 21 connected at their outer ends to the front panel. Each end panel 21 is connected to an inner longitudinally extending bottom rail 22. In like manner, the seat section 12 is provided with a longitudinally extending outer panel 23 and end panels 24 having their front ends connected to the panel 23. The longitudinally extending bottom rail 25 also connects the end panels 24 similarly to the bottom rail 22.

As will be observed, each end panel 21 of the back is provided with an upper extension 26 which extends slightly over into the area of the seat section 12. The inner end of the end panel 24 of the seat section is cut away somewhat to receive the extension 26 of the panel 21. Furthermore, a block 27 is secured to the inner face of the panel 24, preferably by means of dowels 28 (see Figures 1 and 6). The upper edge of this block 27 is preferably contiguous with the upper

edge of the panel 24, and the block extends inwardly beyond the inner end of the panel 24 and overlaps the extension 26 of panel 21. A pair of aligned dowel holes are formed in these overlapping portions to receive the dowel 19 which also passes through a hole in the bracket 18 to form the fixed pivot about which the sections 12 and 13 swing. It will be observed that the inner portion of the seat panel 24 is cut away to provide sufficient clearance to permit the panels 21 and 24 to freely swing about their pivot 19.

Inwardly of the block 27 and extending parallel and in spaced relation thereto is a cross bar 29. The outer end of this bar is secured to the longitudinal panel 23, while the inner end terminates substantially coincident with the inner end of the block 27. An inner longitudinally extending rail 30 (see Figures 1 and 6) has one end secured to the cross bar 29, while its other end is secured to the like cross bar 29 positioned at the opposite end of the frame structure.

The space between the block 27 and the cross bar 29 is sufficiently wide to receive one end of a wooden latch 31. Both the members 27, 29, and the latch, are provided with aligned openings for receiving a dowel 32 constituting a pivot upon which the latch 31 is mounted. The free end of this latch is cut away to form a notched portion 33, and a releasing dog 34 is pivotally mounted on one side of the latch in rear of the notch 33. The free end of this dog 34, however, extends into the area of the notch 33 and is likewise provided with a notch 35 for a purpose to be hereinafter described.

An end rail 36 forming part of the back frame structure is secured to the inner face of its respective end panel 21. The upper face of this rail terminates substantially below the top of the end panel 21 and is preferably smooth, constituting a supporting shelf 37 upon which the free notched end of the latch 31 is adapted to slide when the sections 12 and 13 are moved about the fixed pivot 19 during movement of the sections from one position of adjustment to the other. While this shelf may be substantially straight, I prefer that it be slightly curved or arcuate in construction adjacent its inner end, so that the inner end of the latch is slightly raised above the surface, in the bed position of the seat and back. In this connection, the free end of the elevating dog 34 will rest upon the arcuate portion of the supporting shelf (see Figure 1). I find that the different elements operate more smoothly by having this portion of the rail 36 arcuate.

As will be observed (see Figure 1), the upper surface of the inner end of the rail 36 is cut away to provide a shoulder 38, which shoulder is adapted to be engaged by the notch 33 of the latch 31 to retain the back in its raised operative position, as will be hereinafter described in greater detail. In order to urge the latch into engagement with the rail 36 and to assure that the notch 33 will engage the shoulder 38, a flat wooden leaf spring 39 is provided. This spring has its outer end secured to the top surface 37 of the rail and is sufficiently flexible to permit its being flexed to the position shown in Figure 1, wherein the portion adjacent its free end is in contact with the top of the latch 31 and urges it toward the top surface 37 of the rail 36.

In order to insure that the latch will be free to operate in its accustomed manner and to prevent any clogging action due to accidental penetration of upholstery or other foreign matter be-

tween the latch and the shelf, there is provided a protective casing 40 consisting of a vertical plate or board 41 secured to the inner side face of the rail 36, and a top plate 42 extending over the top of the latch and spring and secured between the plate 40 and the inner wall of the end panel 21. It is to be understood that this covering is not absolutely necessary to the operation of the latch member, and may be omitted if desired.

Referring again to Figures 1 to 6 and assuming that it is desired to move the sections 12 and 13 from their bed position shown in Figure 1 to the sofa or "couch use" position, this is accomplished by initially swinging the seat section 12 about its pivot 19 to the position shown in Figure 2. During the movement of the seat section about its pivot, the latch 31 will slide inwardly upon the top surface 37 of the rail until the notch 33 has dropped into engagement with the shoulder 38. When this has been accomplished, the position of the seat is then reversed. That is, it is swung downwardly to its horizontal position, and because of the interlocking connection between the latch notch 33 and the shoulder 38, the back section will be moved to its normal operative position shown in Figure 3. It will be observed that the construction of the latch and shoulder is such that the pressure exerted on the back when in normal use will have the effect of urging the latch into interlocking engagement with the shoulder. Because of the fact that each latch is of strong sturdy construction and interlocks with the rail shoulder which, in itself, constitutes a portion of the frame structure of the back portion, a relatively solid and rigid construction is provided which will withstand the normal strain and stresses imposed upon the sofa bed.

When it is again desired to move the back and seat sections to their horizontal bed position shown in Figure 1, this may be easily and quickly accomplished by initially swinging the back section 13 to a substantially horizontal position, such as shown in Figure 2. This will simultaneously raise the seat section 12. Thereafter, the seat should be moved further about its pivot to the position shown in Figure 4. It will be observed that with the sections in this position, the latch notch will be moved slightly away from the shoulder 38, while the notch portion 35 of the dog 34 will have dropped into engagement with the shoulder 38. Thereafter, a quick downward pull upon the seat will initially cause the dog 34 to pivot about the shoulder 38. This will cause the dog, together with the free end of the latch, to be raised, so that its notch 33 will clear the shoulder 38. The downward movement of the seat is continued until it reaches its horizontal position, and such movement will slide the latch 31 and the dog 34 inwardly upon the top surface 37 of the rail 36 back to the position shown in Figure 1. These operations may be repeated as often as desired, and in view of the substantial counter-balancing of one section relative to the other, little or no exertion is necessary to change the device from bed to sofa position, or from sofa to bed position.

Referring to Figure 11, there is disclosed a modified form of the invention. In this connection, the seat 43 and back 44 are substantially the same construction as the seat 12 and back 13. Furthermore, the latch 45 is pivoted at 46 upon the seat section similar to the latch 31. This latch is also provided with a notch 47 correspond-

ing to the notch 33. However, instead of employing a dog mounted exteriorly of the latch, such as the dog 34, there is provided a dog 48 pivotally mounted in a centrally disposed recess in the free end of the latch and in advance of the notch 47. A pivot pin 49 constitutes the pivot about which the dog rotates.

A rail 50 is secured to the inner face of the end panel 51, and this rail is provided with a shoulder 52 similar to the shoulder 38. In this modification, however, a notched indentation 53 is also formed in the top surface of the rail, in advance of the shoulder 52.

The same routine is utilized in converting the sofa bed from bed position to sofa or couch-like position as that described hereinbefore. That is, the seat section 43 is initially moved about its pivot to raised position to permit the notch 47 to drop into engagement with the shoulder 52. This will position the free end of the dog 48 directly in advance of the indentation 53. Thereafter, the seat is swung downwardly about its pivot to its horizontal position, and this will simultaneously raise the back to its operative position.

In again converting the device to bed position, the back and seat are moved about their pivot to a position similar to that shown in Figure 2 of the drawings. Thereafter, the seat is moved to the position shown in Figure 4, so as to slide the notch 47 out of engagement with the shoulder 52. This movement will also slide the dog 48 into a position whereby its free end will engage the indentation 53. Thereafter, by a quick downward pull on the seat section, the free end of the dog 48 will pivot in the indentation 53 and at the same time move the dog about its pivot 49. This will have the effect of raising the latch 45, so that its notch will be free of the shoulder 52. By a continued downward movement of the seat portion 43, the latch will continue to slide on the top surface of the rail 50 back to the position shown in Figure 11.

It is to be understood that a spring 54 similar to the spring 39 is secured to the rail 50 and has its free end normally in engagement with the latch 45 to urge the same into engagement with the rail. It is also to be understood that a covering member similar to the cover 40 may be applied to this form of the device.

It is to be further understood that the invention is not limited to the details of construction shown in the drawings, and that the phraseology employed in the specification is for the purpose of description and not of limitation.

I claim:

1. A sofa bed having hinged back and seat sections, each section including an end panel, a rail positioned longitudinally of and adjacent one of said end panels and having a top surface constituting a latch supporting shelf, said rail being provided with a shoulder, a latch pivotally carried by said other section and having a notch formed therein for engagement with said shoulder to maintain the sections in one position of adjustment, said latch being supported on the top surface of said rail and slidable on the same during movement of the sections from one position to another, and means carried by said latch for disengaging the latch notch from the shoulder to permit movement of the sections to another position of adjustment.

2. A sofa bed having hinged back and seat sections, each section including an end panel, a rail positioned longitudinally of and adjacent one of said end panels and having a top surface consti-

tuting a latch supporting shelf, said rail having a shoulder formed thereon adjacent the inner end thereof, a latch pivotally carried by said other section and having a notch formed therein and engageable with the shoulder to maintain the sections in one position of adjustment, said latch being supported on the top surface of said rail and slidable on the same during movement of the sections from one position to another, means carried by said latch for disengaging the latch notch from the shoulder to permit the latch to slide on the rail and thereby allow movement of the sections to another position of adjustment, and a flat leaf spring having one end secured to the rail and its free end engageable with the top of the latch to urge it into contact with the rail shelf.

3. A sofa bed having hinged back and seat sections, each section including a frame having end panels, a rail mounted longitudinally of and adjacent one of said section panels and having a top surface constituting a latch supporting shelf, said rail being provided with a shoulder, a block secured to the inner end of the panel of the other section, a cross-bar spaced from and extending longitudinally of said block and panel, a latch pivotally mounted between the inner ends of said block and cross-bar and having a notch formed therein for engagement with said shoulder to maintain the sections in one position of adjustment, said latch being supported on the top surface of said rail and slidable on the same during movement of the sections from one position to another, and means carried by said latch for disengaging the latch notch from the shoulder to permit movement of the sections to another position of adjustment.

4. A sofa bed having hinged back and seat sections, each section including a wooden frame having end panels, a wooden rail mounted longitudinally of and adjacent one of said section panels and having a top surface constituting a latch supporting shelf, said rail being provided with a shoulder, a wooden latch pivotally carried by said other section and having a notch formed therein for engagement with said shoulder to maintain the sections in one position of adjustment, said latch being supported on the top surface of said rail and slidable on the same during movement of the sections from one position to another, means carried by said latch for disengaging the latch notch from the shoulder to permit movement of the sections to another position of adjustment, and a protective covering for said latch and rail comprising a board secured to the inner face of the rail and extending upwardly therefrom, and a second board bridging the panel and first board and secured thereto.

5. A sofa bed having hinged back and seat sections, each section including an end panel, a rail positioned longitudinally of and adjacent one of said end panels and having a top surface constituting a latch supporting shelf, said rail having a shoulder formed thereon adjacent the inner end thereof, a latch pivotally carried by said other section and having a notch formed therein and engageable with the shoulder to maintain the sections in one position of adjustment, said latch being supported on the top surface of said rail and slidable on the same during movement of the sections from one position to another, means carried by said latch for disengaging the latch notch from the shoulder to permit the latch to slide on the rail and thereby allow movement of the sections to another position of adjustment,

and a flat leaf spring having one end secured to the rail and its free end engageable with the top of the latch to urge it into contact with the rail shelf, the top surface of said rail adjacent the shoulder being curved away from the leaf spring to facilitate operation of the latch and to reduce pressure on said leaf spring when said latch moves from sofa to bed position.

6. A sofa bed having hinged back and seat sections, one section comprising a rectangular frame having side panels and end panels connecting the side panels, a rail extending between and having its ends connected to the side panels, said rail extending longitudinally of and in contact with the inner face of one of the end panels and having a top surface constituting a latch supporting shelf, said rail being provided with a shoulder adjacent its inner end; a latch pivotally mounted on the other section and having a notch formed therein for engagement with said shoulder to maintain the sections in one position of adjustment, said latch being supported on the top surface of said rail and slidable on the same during movement of the sections from one position to

another, and means for disengaging the latch notch from the shoulder to permit movement of the sections to another position of adjustment.

7. A sofa bed having hinged back and seat sections, each section including an end panel, a rail positioned longitudinally of and adjacent one of said panels and having a top surface constituting a latch supporting shelf, said rail having a shoulder formed thereon adjacent the inner end thereof, a latch pivotally carried by said other section and having a notch formed therein and engageable with the shoulder to maintain the sections in one position of adjustment, said latch being supported on the top surface of said rail and slidable on the same during movement of the sections from one position to another, means carried by said latch for disengaging the latch notch from the shoulder to permit the latch to slide on the rail and thereby allow movement of the sections to another position of adjustment, and spring means carried by one of said sections and engageable with said latch to urge it into contact with the rail shelf.

ROBERT ALLEN BURTON.
